Attorney.

UNITED STATES PATENT OFFICE.

ROBERT E. LINHAM, OF MANSFIELD, OHIO; HERMIE LINHAM, EXECUTRIX OF SAID ROBERT E. LINHAM, DECEASED, ASSIGNOR, BY MESNE ASSIGNMENTS, TO THE LINHAM DADO MACHINE COMPANY, OF SAME PLACE.

MOLDING-CUTTER.

SPECIFICATION forming part of Letters Patent No. 472,675, dated April 12, 1892.

Application filed February 14, 1890. Serial No. 340,467. (No model.)

To all whom it may concern:

Be it known that I, ROBERT E. LINHAM, a citizen of the United States, residing at Mansfield, in the county of Richland and State of Ohio, have invented certain new and useful Improvements in Molding-Cutters; and I do declare the following to be a full, clear, and exact description of the invention, such as will enable others skilled in the art to which it applies to make and use the same.

My present invention relates to a cutter for making moldings which is especially adapted for use in a cutter-head of a molding-making machine which forms the subject-matter of a separate application of mine, filed of even date herewith and bearing the Serial No. 340,466; and the object of my invention is to provide a cutter adapted to form a groove in the molding, the sides of which groove or channel are convex.

With this end in view my cutter consists of a cylindrical shank and a foot or blade, which is arranged in line with and forms a continuation of the shank, said foot or blade being flat and somewhat broader than the shank; also the size of the blade varies according to the groove or channel to be cut and having the curved cutting-edges.

In the accompanying drawings, Figure 1 is a perspective view of my improved molding-cutter. Fig. 2 is a side elevation thereof. Fig. 3 is a front view.

Like numerals of reference denote like parts in all the figures.

1 denotes the shank, and 2 the foot or blade, of my molding-cutter. The shank of my improved bit or cutter is made cylindrical in order to adapt it to the cutter-head before named, for which I have filed an application.

The foot or blade is arranged in line with and forms a continuation of the shank, and the blade is made substantially flat, with con-

vex or curved edges 3, which meet at a point at the bottom of the blade, said edges gradually diverging in curved lines from the lower extremity of the foot or blade until they reach points probably two-thirds (more or less) of the length of the blade or foot. One surface of the blade or foot is without a cutting-surface and is in the vertical plane of the face of the shank, and on its rear or interior surface the blade or foot is beveled on a working surface to provide cutting-edges 4.

The cutter is secured in the cutter-head of the molding-machine so that its working face approaches the work as the cutter-head rotates, and the curved cutting-edges remove the wood of the molding to form a groove or channel, which channel conforms in cross-section to the shape of the cutter.

The cutter is of an angular shape, converging toward its lower point to provide a cutting-point with gradually-diverging cutting-edges on each side, thereby reducing resistance, and a converging portion above the side edges to clear the tool from the loose material operated on and at the same time make it possible to construct the groove of curved-sided triangular shape.

Having thus described my invention, what I claim is—

The herein-described molding-cutter, comprising a shank, a flat triangular foot or cutter having a single point and beveled side, and cutting-edges diverging from said point and again converging toward the shank, for the purpose set forth.

In testimony whereof I affix my signature in the presence of two witnesses.

ROBERT E. LINHAM.
